UNITED STATES PATENT OFFICE.

ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

PERCUSSION-FUSE FOR EXPLOSIVE PROJECTILES.

1,301,482.

Specification of Letters Patent. Patented Apr. 22, 1919.

Application filed May 23, 1917. Serial No. 170,546.

To all whom it may concern:

Be it known that I, ALBERT HENRY MIDGLEY, a subject of the King of Great Britain and Ireland, and residing at Warble Way, 5 Acton Vale, in the county of Middlesex, England, have invented certain new and useful Improvements in and Relating to Percussion-Fuses for Explosive Projectiles, of which the following is a specification.

10 This invention relates to percussion fuses for explosive projectiles wherein a safety member is interposed between the striker and the percussion cap, and is retained in its safety position by means provided outside the fuse holder, such as a tape, as in the percussion fuses described in my concurrent applications Nos. 170544 and 170545 and more particularly to the means for retaining the safety member in position and 20 for causing it to be automatically removed after the shell has been fired.

The invention consists in constructing the means for retaining the safety member of a fuse holder of the character above described 25 in position and for causing it to be automatically removed after the shell has been fired, as hereinafter more particularly referred to.

Referring to the accompanying drawings:

Figure 1 is a sectional elevation of the 30 percussion fuse.

Fig. 2 an elevation thereof with the retaining means in position.

Fig. 3 an elevation with the retaining means and safety member removed therefrom.

Fig. 4 is a plan view.

Fig. 5 is a longitudinal view of the tape, showing it attached to the safety member.

Fig. 6 another view of the connection between the safety member and the tape, while 40

Figs. 7 and 8 are an elevation and a plan view of a detail, respectively.

Referring to the drawings, *a* and *b* are 45 two movable blocks carrying the striker *c* and the percussion cap *d* respectively, and mounted within the fuse holder *e*, being separated from each other by a safety member *f* interposed directly between the striker *c* and the percussion cap *d*, and preferably 50 provided with a depression *g* for receiving the striker. *h*, *h* are a pair of springs interposed between the two blocks, for keeping the latter apart after the safety member has been removed from its safety position.

55 The upper surface of the block *a* carrying

the striker is provided with a central conical seat, the end cover *i* of the fuse holder being also provided with a similar conical seat, and a ball *j* being interposed between said block and end cover, the upper and 60 lower surfaces of the ball thus abutting against said conical seats provided on the end cover *i* and the block *a* respectively. The construction of the fuse so far described is identical with the fuse described in my 65 concurrent application No. 170,545.

According to the present invention, the tape described in the latter specification is modified as hereinafter more particularly referred to.

The tape *k* wound around the fuse holder is pivotally attached to the safety member preferably by means of a link or stirrup *l* along an axis substantially parallel to the longitudinal direction of the fuse holder. 75 The tape is continued by a flat spring, preferably a flattened coil spring *m* attached to a set-back pin *n* for automatically releasing the tape on the discharge of the gun. According to a modification, the tape may be 80 entirely dispensed with and be replaced by a spring of the character just referred to. A loose bracket *o* is preferably arranged at the point where the safety member *f* is introduced into the fuse holder and is provided for this purpose with a hole *o*¹ for allowing the safety member to be inserted in between the striker and the percussion cap within the fuse holder. This bracket is 85 kept in position by the tape which is wound 90 around the fuse holder after the safety member *f* attached thereto has been inserted into the fuse holder, and by the two ends of the set-back pin *n* attached to the spring continuation of the tape, which pin is adapted 95 to engage with two lugs *p* and *q* formed on the bracket, the lug *p* being provided for this purpose with a hole *p*¹, and the lug *q* with an open recess *q*¹ and two projections *q*² 100 engaging with a small cross-pin *n*¹ provided on the set-back pin. The tape must be wound in that direction around the fuse holder relatively to the position of the loose bracket thereon, in which the tension of the spring *m* attached to the tape will force the 105 small cross-pin *n*¹ provided on the set-back pin against the projections *q*² on the lug *q* of the bracket, the opposite end of the pin engaging within the hole *p*¹ provided in the lug *p* of the bracket. By this arrangement, 110

the tape is kept tightly around the fuse holder until the set-back pin is automatically pushed back by air pressure when the shell is fired, whereby its two ends are caused to 5 become disengaged from the two lugs formed on the loose bracket, thus permitting the tape to unwind itself from the fuse holder during the flight of the shell and to drop away from the latter, together with the 10 safety member *f* attached thereto and the loose bracket *o*.

An ordinary safety-pin *r* provided with a cord *r*¹ for facilitating its removal is inserted into the set-back pin in such a position 15 that the lug *q* should lie between the safety pin *r* and the small cross-pin *n*¹ on the set-back pin, thereby preventing the set-back pin from being released, as hereinbefore described, until the safety-pin has been 20 removed therefrom.

Another feature of the invention consists in the provision of a vane *s* on the exterior of a sleeve *t* provided around the fuse holder *e* between the latter and the loose bracket *o* 25 above referred to, the sleeve being formed with a hole *t*¹ to permit the insertion of the safety member into the fuse holder. This sleeve and vane arrangement is provided with the object of preventing the entrance of 30 earth, water, or other foreign substance into the interior of the fuse after the tape, together with the safety member attached thereto, have dropped away from the shell, this being effected by the vane *s* being acted 35 upon by air pressure during the flight of the shell, thereby rotating the sleeve *t* around the fuse holder, thus causing the latter to cover the hole in the fuse holder. The vane *s* is preferably made springy and put 40 under tension by the tape, so as to assist in the throwing out of the safety member either directly or through the intermediary of the bracket *o* referred to when the tension thereon is released upon the unwinding 45 of the tape when the shell is discharged. The vane *s* may be attached to the sleeve *t* by cutting and bending out a strip *t*² in the sleeve *t* and by inserting the end *s*¹ between the sleeve and the said strip and bending it 50 over the latter as shown at *s*².

I wish it to be understood that the various features of construction referred to may be modified without departing from the spirit of the invention.

55 What I claim is:—

1. A percussion fuse for explosive projectiles having a fuse holder, two members capable of relative axial movement, a striker provided on one of the members, a percussion cap provided on the other member, a positive safety member for keeping the two members carrying the striker and the percussion cap apart from each other, a tape provided outside the fuse holder for keeping 60 the safety member in its safety position, and

means for pivotally attaching the tape to the safety member, as set forth.

2. A percussion fuse for explosive projectiles having a fuse holder, two members capable of relative axial movement, a striker 70 provided on one of the members, a percussion cap provided on the other member, a positive safety member for keeping the two members carrying the striker and the percussion cap apart from each other, a tape 75 provided outside the fuse holder for keeping the safety member in its safety position, and a link for pivotally attaching the tape to the safety member, as set forth.

3. A percussion fuse for explosive projectiles having a fuse holder, two members capable of relative axial movement, a striker provided on one of the members, a percussion cap provided on the other member, a positive safety member for keeping the two 85 members carrying the striker and the percussion cap apart from each other, a flat spring tape wound around the fuse holder, means for pivotally attaching the tape to the safety member, and a set-back pin attached 90 to the end of the flat spring tape for automatically releasing the tape, as set forth.

4. A percussion fuse for explosive projectiles having a fuse holder, two members capable of relative axial movement, a striker 95 provided on one of the members, a percussion cap provided on the other member, a positive safety member for keeping the two members carrying the striker and the percussion cap apart from each other, a flat 100 spring tape attached to the safety member and wound around the fuse holder, a set-back pin attached to the end of the flat spring tape for automatically releasing the tape, and a loose bracket adapted to receive 105 the set-back pin, as set forth.

5. A percussion fuse for explosive projectiles having a fuse holder, two members capable of relative axial movement, a striker provided on one of the members, a percussion cap provided on the other member, a positive safety member for keeping the two members carrying the striker and the percussion cap apart from each other, a flat 110 spring tape attached to the safety member and wound around the fuse holder, a set-back pin attached to the end of the flat spring tape for automatically releasing the tape, a loose bracket adapted to receive the set-back pin, said bracket having lugs adapted to receive the ends of the set-back pin, and projections on one of the lugs, and a small cross-pin being provided on the set-back pin and adapted to engage with the said projections on one of the lugs, as set forth. 115

6. A percussion fuse for explosive projectiles having a fuse holder, two members capable of relative axial movement, a striker on one of the said members, a percussion cap provided on the other member, a positive 120

125

130

safety member for keeping the said two members apart from each other, a hole in the fuse holder for the insertion of the positive safety member, means provided outside the fuse holder for keeping the positive safety member in position, a sleeve mounted on the outside of the fuse holder, a hole provided in said sleeve through which the positive safety member is inserted into the fuse holder between the striker and the percussion cap and a vane on the sleeve, as and for the purpose set forth.

7. A percussion fuse for explosive projectiles having a fuse holder, two members capable of relative axial movement, a striker on one of the said members, a percussion cap provided on the other member, a posi-

tive safety member for keeping the said two members apart from each other, a flat spring tape attached to the safety member and wound around the fuse holder, a set-back pin attached to the flat spring tape, a loose bracket receiving the set-back pin, a sleeve mounted on the outside of the fuse holder, a hole in the fuse holder and a hole in the sleeve through which the positive safety member is inserted into the fuse holder between the striker and the percussion cap, and a vane on the sleeve, said vane being arranged underneath the loose bracket, as and for the purpose set forth.

In testimony whereof I have signed my name to this specification.

ALBERT HENRY MIDGLEY.
